UNITED STATES PATENT OFFICE.

ROBERT J. WORKMAN, OF SAN FRANCISCO, CALIFORNIA.

CAN-STUFFING MACHINE.

1,311,144.

Specification of Letters Patent. Patented July 22, 1919.

Application filed September 5, 1917. Serial No. 189,889.

To all whom it may concern:

Be it known that I, ROBERT J. WORKMAN, a citizen of the United States, residing in the city and county of San Francisco and State of California, have invented a new and useful Improvement in Can-Stuffing Machines, of which the following is a specification.

My invention relates to improvements in can-stuffing machines wherein a can conveying draper operates in conjunction with can arresting mechanism and stuffing mechanism to stuff a portion of the contents of a hopper into said can; and the objects of my invention are,

First, to provide an improved can stuffing machine;

Second, to provide a simple and improved can arresting mechanism adapted to arrest cans on a draper and under a filling or stuffing spout;

Third, to provide a simple, efficient and improved means for conveying a viscous material from a hopper into a can;

Fourth, to provide an improved adjustable mechanism to force or feed various predetermined amounts of a viscous material into a can or the like.

I accomplish these several objects by means of the preferred form of the device disclosed in the drawings forming a part of the present specification wherein like characters of reference are used to designate similar parts throughout the said specification and drawings and in which—

Figure 1 is a broken plan view of my improved stuffing machine, a portion of the hopper being in section;

Fig. 2 is a broken front elevation;

Fig. 3 is a transverse sectional view of the machine;

Fig. 4 is a detailed view of the controlling cans for the operating of the stuffing conveyer; and

Fig. 5 is a section taken on line 5—5 of Fig. 3 in the direction indicated.

Referring to the drawings the numeral 1 is used to designate a suitable frame to the upper portion of which is secured a hopper 2, having a dispensing spout 3 with a depending portion 4 thereto.

Rotatably mounted within the hopper 2 and spout 3 is a worm conveyer 6 whose shaft 7 extends beyond the spout 3 and is provided with a chain sprocket 8.

A draper 9 is mounted upon suitable

rollers 11 operated from an independent source, not shown, and is arranged to carry cans 12 under and past the depending portion 4 of the spout 3, the purpose of which will hereinafter be more fully described.

A shutter 14 is arranged under the portion 4 of the spout 3 and is pivotally mounted upon the frame 1 as at 16. The other end of the shutter 14 is connected to an operating lever 17 pivotally mounted as at 18 and arranged to be operated by means of a cam 19 and on a driving shaft 20 rotatably mounted within the lower portion of the frame 1.

The shutter 14 is normally held in a closed position by means of a suitable spring 34, secured above the fulcrum or pivotal point 18 of the operating lever 17, the other end of said spring 24 being secured to a suitable standard 33 mounted on a portion of the frame 1 as disclosed in Fig. 2 of the drawings. The shaft 20 is provided with loose and driving pulleys 22 and 23 respectively, and a gear 24.

A counter shaft 26 is rotatably and pivotally mounted to swing in a horizontal plane to carry a gear 27 into and out of mesh with the gear 24 on the driving shaft 20 but such engaging relation is normally prevented by means of an adjustable cam plate 29, on the shaft 20, provided with slidably mounted sections 31 and 32.

A spring 36 secured to the shaft 20 and counter shaft 26 tends to hold a roller 37 on the counter shaft 26 onto the peripheries of the cam plate 29 and the sectors 31 and 32 so that when the space between the ends of the said cam sectors 31 and 32 is encountered by the rotation of the shaft 20 the tension of said spring 36 will move the gear 27 into mesh with the gear 24 and thereby rotate the counter shaft 26.

The counter shaft 26 is also provided with a sprocket 38 provided with a chain 39 connecting with the sprocket pinion 8 on the outer end of the worm shaft 7.

The cans 12 are guided in a precise path directly under the spout 3 and depending portion 4 thereof by means of strips 41 so as to properly align the said cans 12 to receive the contents from said spout.

The operation is as follows:

In the present instance the hopper is filled with a viscous mass a predetermined portion 110 of which is to be deposited into successive cans 12 as their progress is temporarily ar-

rested under the depending portion 4 of the spout 3.

The draper 9 is moved at a constant speed to carry the cans between the guiding strips 41 and directly under the depending portion 4 of the spout 3. As a can 12 approaches a point directly beneath the depending spout 4 its further progress is temporarily arrested by the slideable rod 23 which is moved transversely across the path of the can, to arrest said can and impede further progress, by means of the cam 21 on the driving shaft 20 and the operating rod or lever 22.

Simultaneously the cam 19 operates the operating lever 17 to open the shutter 14 under the spout 4 as disclosed in dotted lines in Fig. 5 of the drawings, and against the tension of the spring 34. At the same time the sector plate 32 permits the spring 36 to move the roller 37 and counter shaft 26 to a position where the gear or pinion 27 on said shaft 26 will mesh with and be driven by the gear 24 on the shaft 20.

This will cause the counter shaft 26 and the worm conveyer 6 to be rotated to force or convey a portion of the viscous mass or contents of the hopper 2 through the spout 3 and depending portion 4 thereof into the can 12.

The amount of viscous contents conveyed from the hopper 2 to the can 12 will be in direct proportion to the space between the end of the sector 32 and the beginning of the sector 31. As these sectors overlap at their adjacent ends, as disclosed in Figs. 1, 2, 3 and 4 of the drawings, it is obvious that a continuous periphery will be formed of the adjoining sectors 31 and 32 to prevent the meshing of the gears 27 and 24. As these sectors are slidably mounted upon the cam plate 29 it is obvious that the operating period of the conveyer 6 to convey a portion of the viscous mass into the cans 12 will vary as the space between the open ends of the sectors 31 and 32 is adjusted.

Therefore the predetermined amount of the contents of the hopper 2 be forced or conveyed into the cans 12 may also be adjusted and varied for various size cans.

When the requisite amount of matter has been forced into the cans 12 simultaneously the beveled or inclined end 43 of the sector 31 will engage the roller 37 and unmesh or disengage the gear 27 from the gear 24 to prevent the further operation of the conveyer 6 and the feeding or conveying of the contents of the hopper 2 into the can 12; the cam 19 will operate the operating lever 17 to permit the spring 32 to close the shutter 14; and the cam 21 will operate the rod 23 and withdraw the same from the path of the can 12 thereby permitting the draper 9 to convey said can from under and past the depending portion of the spout 3.

As soon as the approximate center of the

released can 12 has passed the center line of the spout 4 the cam 21 again operates to arrest the progress of successive cans and the above described operation is repeated.

It is obvious from the foregoing that I have provided an improved can stuffing machine adapted to feed or convey predetermined amounts of a viscous content from the hopper into successive cans as well as improved means for temporarily arresting the progress of the cans, and adjustable means for determining the amount of the contents to be deposited.

I am aware that the present state of the art discloses can stuffing machine wherein a can is temporarily arrested under a filling spout. I therefore do not claim such a combination broadly, but

Having thus described my invention what I claim as new and desire to secure by Letters Patent is—

1. A can stuffing machine comprising a hopper; a filling spout connected to the hopper; a draper to carry cans under and past the spout; a shutter secured to the spout to normally prevent the passage of contents from the hopper; a conveyer to convey the contents from the hopper to a can under the spout; means for arresting cans under the spout; and means for operating the shutter, conveyer and can arresting means whereby a portion of the contents from the hopper may be deposited through the spout into successive cans.

2. A can stuffing machine comprising a hopper; a dispensing spout connected to the hopper; a shutter secured to the spout; a conveyer to convey contents from the hopper to the spout; a draper to convey cans under and past the spout; a can arresting mechanism to arrest the passage of cans under the spout; and means for operating the shutter, conveyer and can arresting means intermittently to deposit contents from the hopper into successive cans.

3. A can stuffing machine comprising a hopper; a dispensing spout connected to the hopper; a shutter secured to the spout to normally close the same; a conveyer within the hopper and spout to convey contents from said hopper and through said spout; a draper to carry cans under and past the spout; a slideable rod arranged to arrest the passage of cans on the draper; a driving shaft; a cam on the shaft to operate the spout shutter; a second cam on said shaft to operate the slideable rod to temporarily arrest the passage of cans on the draper while the spout shutter is operated; and means for operating the conveyer to convey contents from the hopper into successive arrested cans.

4. A can stuffing machine comprising a suitable frame; a hopper arranged on the upper portion of the frame; a spout con-

- 5 nected to the hopper; a conveyer for conveying the hopper contents to the spout; a normally closed shutter on the spout; a draper arranged under the spout to carry 55 cans under and past said spout; a rod slidably mounted adjacent and transversely to the draper; a driving shaft mounted within the frame; a cam on the shaft operatively connected to the slideable rod to move said 60 rod intermittently to arrest cans on the draper and under the spout; a second cam on the shaft operatively connected to the shutter to open said shutter when a can is arrested thereunder; a gear upon the driving shaft; a counter shaft rotatably and pivotally mounted within the frame and operatively connected to the conveyer; a gear on the counter shaft; and means for meshing the gears on the counter and driving 65 shafts to operate the conveyer when a can is arrested under the spout and the shutter is operated.
- 10 5. A can stuffing machine comprising a suitable frame; a hopper arranged in the upper portion of the frame; a spout connected to the hopper; a conveyer within the hopper and spout for conveying the contents of said hopper into and forcing the same through the spout; a normally closed shutter on the spout; a draper to convey cans under and past the spout; a transversely arranged rod slidably mounted adjacent the draper; a driving shaft rotatably mounted within the frame; a cam on the shaft to operate the slideable rod and move the same across the draper to arrest a can under the spout; a second cam on the shaft to open the shutter when a can is arrested under the spout; a gear upon the drive shaft; a counter shaft rotatably and pivotally mounted within the frame to swing in a horizontal plane; a sprocket chain operatively connecting the conveyer with the counter shaft; a second gear upon the counter shaft arranged to mesh with the first mentioned gear; and adjustable means for permitting the meshing of the gears to operate the conveyer only when the shutter is opened and a can arrested under the spout. 75
- 15 6. A can stuffing machine comprising a suitable frame; a hopper arranged in the upper portion of the frame; a spout connected to the hopper; a conveyer within the hopper and spout for conveying the contents of said hopper into and forcing the same through the spout; a normally closed shutter on the spout; a draper to convey cans under and past the spout; a transversely arranged rod slidably mounted adjacent the draper; a driving shaft rotatably mounted within the frame; a cam on the shaft to operate the slideable rod and move the same across the draper to arrest a can under the spout; a second cam on the shaft to open the shutter when a can is arrested under the spout; a gear upon the drive shaft; a counter shaft rotatably and pivotally mounted within the frame to swing in a horizontal plane; a sprocket chain operatively connecting the conveyer with the counter shaft; a second gear upon the counter shaft arranged to mesh with the first mentioned gear; and adjustable means for permitting the meshing of the gears to operate the conveyer only when the shutter is opened and a can arrested under the spout. 80
- 20 7. A can stuffing machine comprising a suitable frame; a hopper arranged in the upper portion of the frame; a spout connected to the hopper; a conveyer within the hopper and spout for conveying the contents of said hopper into and forcing the same through the spout; a normally closed shutter on the spout; a draper to convey cans under and past the spout; a transversely arranged rod slidably mounted adjacent the draper; a driving shaft rotatably mounted within the frame; a cam on the shaft to operate the slideable rod and move the same across the draper to arrest a can under the spout; a second cam on the shaft to open the shutter when a can is arrested under the spout; a gear upon the drive shaft; a counter shaft rotatably and pivotally mounted within the frame to swing in a horizontal plane; a sprocket chain operatively connecting the conveyer with the counter shaft; a second gear upon the counter shaft arranged to mesh with the first mentioned gear; and an adjustable cam arranged to permit the meshing of the gears to operate the conveyer only when the shutter is opened and a can is temporarily arrested under said spout. 85
- 25 8. A can stuffing machine comprising a suitable frame; a hopper arranged in the upper portion of the frame; a spout connected to the hopper; a conveyer within the hopper and spout for conveying the contents of said hopper into and forcing the same through the spout; a normally closed shutter on the spout; a draper to convey cans under and past the spout; a transversely arranged rod slidably mounted adjacent the draper; a driving shaft rotatably mounted within the frame; a cam on the shaft to operate the slideable rod and move the same across the draper to arrest a can under the spout; a second cam on the shaft to open the shutter when a can is arrested under the spout; a gear upon the drive shaft; a counter shaft rotatably and pivotally mounted within the frame to swing in a horizontal plane; a sprocket chain operatively connecting the conveyer with the counter shaft; a second gear upon the counter shaft arranged to mesh with the first mentioned gear; and an adjustable cam arranged to permit the meshing of the gears to operate the conveyer only when the shutter is opened and a can is temporarily arrested under said spout. 90
- 30 9. A can stuffing machine comprising a suitable frame; a hopper arranged in the upper portion of the frame; a spout connected to the hopper; a conveyer within the hopper and spout for conveying the contents of said hopper into and forcing the same through the spout; a normally closed shutter on the spout; a draper to convey cans under and past the spout; a transversely arranged rod slidably mounted adjacent the draper; a driving shaft rotatably mounted within the frame; a cam on the shaft to operate the slideable rod and move the same across the draper to arrest a can under the spout; a second cam on the shaft to open the shutter when a can is arrested under the spout; a gear upon the drive shaft; a counter shaft rotatably and pivotally mounted within the frame to swing in a horizontal plane; a sprocket chain operatively connecting the conveyer with the counter shaft; a second gear upon the counter shaft arranged to mesh with the first mentioned gear; and an adjustable cam arranged to permit the meshing of the gears to operate the conveyer only when the shutter is opened and a can is temporarily arrested under said spout. 95
- 35 10. A can stuffing machine comprising a suitable frame; a hopper arranged in the upper portion of the frame; a spout connected to the hopper; a conveyer within the hopper and spout for conveying the contents of said hopper into and forcing the same through the spout; a normally closed shutter on the spout; a draper to convey cans under and past the spout; a transversely arranged rod slidably mounted adjacent the draper; a driving shaft rotatably mounted within the frame; a cam on the shaft to operate the slideable rod and move the same across the draper to arrest a can under the spout; a second cam on the shaft to open the shutter when a can is arrested under the spout; a gear upon the drive shaft; a counter shaft rotatably and pivotally mounted within the frame to swing in a horizontal plane; a sprocket chain operatively connecting the conveyer with the counter shaft; a second gear upon the counter shaft arranged to mesh with the first mentioned gear; and an adjustable cam arranged to permit the meshing of the gears to operate the conveyer only when the shutter is opened and a can is temporarily arrested under said spout. 100

In witness whereof I hereunto set my signature.

ROBERT J. WORKMAN.
